[57] CLAIM

The ornamental design for a base for a bottle, as shown and described.

DESCRIPTION

FIG. 1 is a front and rear elevational view of a base for a bottle embodying our ornamental design;

FIG. 2 is a right and left side elevational view thereof;

FIG. 3 is a top plan view thereof;

FIG. 4 is a bottom plan view thereof;

FIG. 5 is a front and rear elevational view of a bottle embodying another embodiment of our ornamental design;

FIG. 6 is a right and left side elevational view thereof;

FIG. 7 is a top plan view thereof;

FIG. 8 is a bottom plan view thereof;

FIG. 9 is an enlarged sectional view taken along line 9—9 of FIG. 3;

FIG. 10 is an enlarged sectional view taken along line 10—10 of FIG. 3;

FIG. 11 is an enlarged sectional view taken along line 11—11 of FIG. 7; and,

FIG. 12 is an enlarged sectional view taken along line 12—12 of FIG. 7.

The broken line portion of the attached drawings shows the general environment of the ornamental design while the full line representation is the claimed invention.
